(57) **CLAIM**

The ornamental design for a cable connector, as shown and described.

DESCRIPTION

FIG. 1 is a perspective view of a cable connector, showing my new design;

FIG. 2 is a front view of the cable connector shown in FIG. 1;

FIG. 3 is a rear view of the cable connector shown in FIG. 1;

FIG. 4 is a side view of the cable connector shown in FIG. 1; the opposite side of the view shown in FIG. 4 is a mirror image of the side view shown; and,

FIG. 5 is a top view of the cable connector shown in FIG. 1; a bottom view of the cable connector shown in FIG. 1 is a mirror image of the top view shown.

The broken lines showing a pin and a head next to the pin in FIGS. 1, 2, 4 and 5 and a cable line in FIGS. 1, and 3 through 5 are for illustrative purposes only and form no part of the claimed design.
